FIG. 2.

۳۵۶

BENJAMIN BROIDO

Inventor

By HIS Attorney O. I. Thiele

UNITED STATES PATENT OFFICE.

BENJAMIN BROIDO, OF PERTH AMBOY, NEW JERSEY, ASSIGNOR TO THE SUPER-HEATER COMPANY, OF NEW YORK, N. Y., A CORPORATION OF DELAWARE.

ECONOMIZER.

Application filed April 29, 1920. Serial No. 377,655.

To all whom it may concern:

Be it known that I, BENJAMIN BROIDO, a citizen of the United States, residing at Perth Amboy, in the county of Middlesex and State of New Jersey, have invented certain new and useful Improvements in Economizers, of which the following is a specification.

The present invention relates to economizers.

The material used for these structures practically universally in the United States is cast iron. When the feed water has no scale-forming ingredients, and is fed to the economizer at a temperature of from 90 to 100° F., this material is entirely satisfactory for this purpose. There is of course the limitation that the cast iron economizer must not be subjected to any considerable pressures. This limitation does not apply to economizers made of steel; but otherwise the difficulties encountered when cast iron is used are even more pronounced in the case of economizers made of steel. In either case the use of water of scale-forming properties causes deposits difficult to remove; and in either case the use of water below the temperature named results in condensation on the exterior of the cooler parts of the economizer of moisture in the products of combustion, with the result of corrosion which will be especially rapid where there is a high sulphur content in the coal.

Steel economizers are in addition much more subject to internal pitting where considerable air, or gaseous acids, or organic matter are contained in the feed water, a condition very likely to exist in the case of surface water.

Where it is necessary to furnish cold water to the economizer, i. e., water below about 90° F., the only effective way so far proposed to my knowledge of preventing the objectionable formation of condensed moisture spoken of is to mix enough boiler water with the cold feed water to raise the temperature of the latter above the point where such condensation occurs. This involves a loss of efficiency in the operation of the economizer.

The internal pitting, most pronounced with steel economizers, may be more or less effectively prevented by the addition to the

water of neutralizing chemical agents, such as carbonate of soda or lime; but it is usually found that if such materials are added in quantities sufficient to have the desired neutralizing effect the boiler water soon becomes such a concentrated solution as to endanger the boiler plates.

It is the purpose of the present invention to obviate some of the difficulties pointed out.

The invention is illustrated in the drawings, in which Fig. 1 represents more or less diagrammatically in longitudinal section a boiler with an economizer according to my invention; Fig. 2 is an enlarged view of a portion of Fig. 1; and Fig. 3 is a fragmentary view on line 3—3 of Fig. 2.

The boiler shown is of a well-known type. It comprises a lower drum 1, and the three upper drums 2, 3, 4, the latter connected to the former by three banks of tubes 5, 6 and 7. Gases from the furnace 8 pass successively over these banks, being directed in their course by the baffles 9, 10 and 11, and leaving the boiler proper at 12. Feed water is delivered into the drum 4, and steam is taken off from drum 3. The housing 13, which encloses the boiler proper, is shown extended so as also to accommodate the economizer.

This economizer consists of two sections. The one directly behind the boiler is made up of the upper drum 14, the lower drum 15, and the banks of tubes 16 and 17 connecting them. A partition 18 in the upper drum divides it into the two parts 19 and 20, the former communicating with the upper ends of the tubes in bank 16, the latter with those of the tubes in bank 17. 21 is a connection for the entrance of the feed water, and 22 is a pipe delivering the heated feed water to drum 4 of the boiler.

A baffle 23 extends downward from drum 14 between banks 16 and 17, terminating some distance above drum 15.

The other section of the economizer comprises an upper drum 25, a lower drum 26, and a bank of tubes 27 connecting them.

A pipe 28 connects the upper drum 25 to a header 29 which lies adjacent and parallel to drum 14. The lower drum 26 is connected to a second similar header 30 by the pipe 31.

The headers 29 and 30 have connected to them a series of alined serpentine coils 32. Where the ends of these coils extend through the wall of the drum 14 they are expanded 5 or made tight by any other means desired, the ends being rolled into, or otherwise secured to, the headers 29 and 30.

It will be noted that drums 25 and 26, tubes 27 connecting them, pipes 28 and 31, 10 headers 29 and 30, and coils 32 constitute a closed, self-contained system, not communicating with the other section of the feed water heater. This system is kept completely filled with water, preferably distilled, any loss from leakage being made up through the valved connection 33.

Under the coils 32 in compartment 20 there is a pan 36 running lengthwise of the drum, within and near the bottom of which 20 is located a pipe 37 provided with perforations 38, and extending out through the end of the drum to some convenient point of discharge. This pipe 37 is at some accessible point provided with a valve 39.

25 From an elevated point of chamber 20 there extends outward the valved pipe 40, terminating at some appropriate point.

A baffle 24 extends upward from drum 26 in front of the bank of tubes 27, terminating 30 some distance below drum 25.

34 indicates the connection for the passage of gases to the stack.

The operation of the apparatus is as follows:

35 Gases leaving the boiler proper at 12 pass successively over the two economizer sections, being guided in their course by the baffles 23 and 24, and finally leaving for the stack through the connection 34.

40 Feed water is supplied under pressure through pipe 21, enters chamber 20, travels downward through tubes 17 to drum 15, upward through tubes 16 to chamber 19, and thence by pipe 22 to drum 4 of the boiler.

45 In compartment 20 it is given an initial heating by coming into contact with the coils 32, thus entering the tubes 17 at a temperature high enough to prevent the condensation on the outside of these tubes 50 of the moisture present in the products of combustion. This preliminary heating results in the precipitation of some sediment which collects in pan 36 and is removed from time to time by blowing it off through pipe 37. At the same time gases may be 55 liberated, which are allowed from time to time to escape through pipe 40.

The water in coils 32 is cooled by the feed water coming into contact with the outside 60 of the coils, while the gases sweeping over tubes 27 impart heat to the water in these tubes. The resultant difference in density sets up the necessary circulation in the closed system so that the heat absorbed from the 65 gases in passing over tubes 27 is constantly

transferred to the feed water entering drum 14. If the circulation should prove inadequate a pump is used to accelerate it.

The temperature of the water in tubes 27 is high enough to prevent any condensation 70 of moisture on their outside surface.

My invention will be seen to remove the difficulties spoken of. It makes steel available as material for economizers. Condensation of moisture in the gases and its 75 deposition on the economizer is prevented; scale forming matter is precipitated and removed before the feed water enters the economizer tubes; gases that are liberated are removed; the economizer may, where desired, be subjected to high internal pressure; and at the same time the temperature of the gases before their final discharge is reduced 80 at least as far as in apparatus as hitherto used.

What I claim is:—

1. In apparatus of the class described, the combination of a boiler; an economizer section; means to supply feed water to it, and means to convey water from it to the boiler; 90 a second economizer section; means to bring the waste gases from the boiler into contact first with the first and then with the second section; and means to transfer heat from the water in the second section to the feed 95 water without mingling the two and before the feed water is heated by the gases coming into contact with the first section.

2. In apparatus of the class described, the combination of a boiler; an economizer section; means to supply water to the section, and means to convey water from it to the boiler; a second economizer section; means to bring the waste gases from the boiler into contact first with the first and then with the second section; heat transferring means adapted for the circulation of water thru them arranged to deliver heat to the feed water before it is heated in the first section by gases; and means to supply heated water to said heat transferring means from the second section and to return the cooled water to the second section.

3. In apparatus of the class described, the combination of a boiler; an economizer section; means to supply water to the section, and means to convey water from it to the boiler; a closed system comprising a second economizer section, a heat transferring device, and means to permit circulation from one to the other and back; and means to bring the waste gases from the boiler into contact first with the first and then with the second section; the heat transferring device being arranged to heat the feed water before it is heated in the first section by waste gases.

4. In apparatus of the class described, the combination of a boiler, an economizer section; means to supply water to the section,

and means to convey water from it to the boiler; a closed system comprising a second economizer section, a heat transferring device, and means to permit circulation from one to the other and back, said system being filled with relatively pure water; means to bring the waste gases from the boiler into contact first with the first and then with the second section; the heat transferring device being arranged to heat the feed water before it is heated in the first section by waste gases; means to make up any leakage from the closed system; and means to blow off precipitates and to allow liberated gases to escape from the feed water before the water is heated by the gases.

BENJAMIN BROIDO.
